(57) **CLAIM**

The ornamental design for a case of air freshener for a car, as shown and described.

DESCRIPTION

FIG. 1 is a top, front and right side perspective view of a case of air freshener for a car;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines, if any in the figures, depict portions of the case of air freshener for a car that form no part of the claimed design.
